UNITED STATES PATENT OFFICE.

WILLIAM H. SEAMON, OF ROLLA, MISSOURI.

INSULATOR.

SPECIFICATION forming part of Letters Patent No. 430,696, dated June 24, 1890.

Application filed February 17, 1890. Serial No. 340,822. (No model.)

To all whom it may concern:

Be it known that I, WILLIAM H. SEAMON, of Rolla, in the county of Phelps, State of Missouri, have invented certain new and useful 5 Improvements in Electric-Wire Insulators and Supports, of which the following is a full, clear, and exact description, reference being had to the accompanying drawings, forming a part hereof.

10 My invention relates to that class of insulating supports commonly made of glass and adapted to be secured in place upon cross-arms; and it consists in the improved construction, combination, and arrangement of 15 parts hereinafter set forth, and pointed out in the claims.

In the drawings, Figure 1 is an enlarged perspective view of the insulator. Fig. 2 is a view of an ordinary pole having cross-arms 20 with my improved insulators applied thereto. Fig. 3 is an enlarged end view of an insulator, and Fig. 4 is a longitudinal section through the same on line $x-x$ of Fig. 3.

Heretofore insulators for cross-arms and 25 the like were usually made hollow and screwed upon a threaded pin carried by the arm, so as to assume a vertical position, or else they were provided with an external thread and screwed into threaded apertures in the cross- 30 arm, so as to still retain the vertical position with relation to the arm and the pole, and the electrical conductors were "tied" to the exterior of such insulators, as in the case of United States Patent No. 107,075. The difficulty incurred by all such constructions was 35 the fact that the "tie-wires" would sometimes break, permitting the heavily-charged conductors to fall to the ground, endangering in many cases the lives of human beings, all as 40 is well known. To overcome such difficulty is one of the objects of my invention, and I do it by providing suitable passages through the insulator, in which the tie-wire and also the conductor are firmly located and secured.

45 1 represents a series of the usual cross-arms, but which instead of having the ordinary vertical pins projecting from their upper surfaces, have a series of horizontal holes a , which are threaded for reception of the insulators,

or which may be devoid of threads, leaving 50 the threads upon the insulator to cut a thread in them, as may be preferred.

2 is the insulator, which should be made of glass, porcelain, or similar material possessing insulating properties, and which is in the 55 form of a comparatively-perfect cylinder of like diameter at each end, so as to adapt its ends for use interchangeably, as will presently be explained. Thus it is that the device is of cylindrical form, provided with a 60 screw-thread 3 upon its exterior extending continuously from terminal to terminal, and having a larger passage 4, extending likewise from end to end through said insulator, in which the conductor is to be located and held, 65 and also a smaller passage 5 similarly formed, but located in a vertical plane that is relatively above or over said larger passage, this last passage being adapted for engagement by the tie-wire. 70

The operation or function is as follows: When an insulator is to be mounted in a cross-arm, a suitable horizontal and transverse passage is made through said cross-arm, and the insulator is screwed therein by 75 any suitable wrench or implement, so that it will lie in a horizontal plane with its passages extending in the direction in which the wires run, as shown in Fig. 2. Then after the insulator has been placed with its smaller passage 80 upward, preferably, the electrical conductor is to be run through the larger passage 4 and securely tied by means of an ordinary tie-wire, which is run through the smaller passage 5 and has its ends twisted 85 around the said conductor.

I do not broadly claim an insulator with screw-threads upon its outer surface, as that alone is clearly shown in the patent hereinbefore mentioned.

Having thus described my invention, what I claim is—

1. A cylindrical insulator for electrical conductors, adapted to be bodily located in a cross-arm or support and having a longitudinal passage or bore extending from terminal to terminal for reception of the conductor and having an additional parallel 95

passage similarly formed and located, and a tie-wire located in said additional passage, substantially as set forth.

2. The insulator having an exterior screw-thread and parallel passages for conductor and tie wire, formed integrally, substantially as hereinbefore set forth.

3. A cylindrical insulator having an external screw-thread and internal passage-way, in combination with a support, such as a cross-

arm in which it is bodily located or embedded with its passage-way extending in a line with the conducting-wire, substantially as set forth.

In testimony whereof I affix my signature in presence of two witnesses.

WILLIAM H. SEAMON.
